MACHINE FOR SHOEMAKING

Louis Sabo, New York, N. Y., assignor to Herman B. Delman, New York, N. Y.

Application September 26, 1940, Serial No. 358,442

12 Claims. (Cl. 12—17)

My invention relates to the art of shoemaking.

One of the principal objects of the invention is to provide means by which women's shoes may be made at a lower cost.

Another principal object is to provide a machine in which means are provided for forming the breast flap of a shoe integral with the sole and shaped to conform in height and contour with the breast of a heel of selected pattern, said forming being accomplished when the heel is in its final fixed position on the shoe.

Another object is to provide such a machine which may be easily set and adjusted to cause the flap to fit accurately the breast of the heel.

Another object is to provide such a machine which may be operated by unskilled persons, after being set by a skilled artisan.

Another object is to overcome the danger of injury to the heel itself which exists in the manual trimming operation heretofore used in forming the flap.

Another object is to provide definitely adjustable means for guiding and positioning the shoe, flap and heel relative to a cutting die, depending on whether a right or a left shoe is to be operated upon.

Another object is to provide a machine in which the positioning of the shoe therein does not depend upon the use of a pintle or the like engaging a hole in the last carrying said shoe, thereby eliminating the necessity for uniformity in the location of pintle-engaging holes in various lasts, and also thereby reducing the cost which may be involved.

Another object is to provide a machine in which a shoe may be positioned and worked upon without a last in said shoe.

Another object is to provide means for removing the scrap or trim remaining after cutting the flap.

Another object is to reduce the number of operations in the manufacture of a shoe.

Further objects and advantages of the invention will be in part set forth in the following specification, and in part will be obvious thereto without being specifically pointed out.

In making shoes for women, heels are used which differ in length, width, and form of the breasts, and it has been the general practice to make the flap of greater width than that of the breast of the heel, and after the flap has been cemented to the breast, to trim the laterally extending portions with a knife by manual operation, which requires time, and also requires

skill to prevent cutting the heel in the act of removing the trim.

I have a co-pending application, Serial No. 328,772, filed April 9, 1940, for improvements in machines for shoemaking, which relates to a machine for cutting the breast flap prior to affixing the heel to the shoe; the present invention differs from the said previous invention both in structural means employed which are adapted to operate upon a shoe to which the heel has been affixed and to form the flap after affixing the heel.

With the above and other objects of the invention in view, the invention consists in the novel construction, arrangement and combination of various devices, elements and parts, as set forth in the claims hereof, certain embodiments of the same being illustrated in the accompanying drawings and described in this specification.

Referring to the drawings which form a part of the specification:

Fig. 1 is a plan view of a machine constructed according to one embodiment of my invention, a part of the cover plate of the housing being broken away and the scrap-removing means not being shown;

Fig. 2 is a front elevation of the same, the shoe-supporting slide being removed;

Fig. 3 is a rear view of said shoe-supporting slide, removed from the machine;

Fig. 4 is a longitudinal vertical section along the line 4—4 of Fig. 1, also showing a shoe supported in place with its unformed flap in position to be formed;

Fig. 5 is a detail view on a relatively enlarged scale of an adjustable device for indicating the desired extent of movement of the shoe-supporting slide;

Fig. 6 is a view, also on a relatively enlarged scale, of the top member of the shoe-supporting slide;

Fig. 7 is a longitudinal vertical sectional view taken along the line 7—7 of Fig. 8, showing a modified form of the slide;

Fig. 8 is a bottom view of the same;

Fig. 9 is a plan view, on a relatively reduced scale, of the holder of the shoe-supporting slide, seen in the direction indicated by arrow 9 in Fig. 7;

Fig. 10 is an elevation of the shoe-supporting member of said slide, seen in the direction of the arrow 10 in Fig. 7;

Fig. 11 is a side elevation of the machine, with the upper die in its lower position, including

means for removing the trim by compressed air, after cutting the flap;

Fig. 12 is a plan view of the same, with the upper die and springs removed; and

Fig. 13 is a detail view in perspective of the lever forming part of said trim-removing means.

In the embodiment illustrated in Figs. 1 to 6 of the drawings, I provide a housing, comprising a base-plate 15, side walls 16, and a top plate 17, which top plate carries a lower die member 18 designed to form a flap when the upper die member 20 is forced into operative engagement therewith. The upper die can be actuated by a hand or machine press, or any other suitable means, not shown in the drawings. The base-plate 15 of the housing is secured to the platform of such a press, or other means chosen, in detachable relation.

21 indicates vertically extending pillars, secured to the base plate 15, which support springs 22, which in turn carry a laterally extending plate 23, fixed to depending tubular guides 24 which are slidable on the pillars 21, which extend therethru, and which plate 23 carries the upper die 20. As shown, the lower die 18 is formed integral with the plate 17, but may instead be carried by said plate.

The space between the edges of the lower die 18 is filled by member 19, the upper surface of which is flush with the upper surface of the plate 17 and which follows substantially the shape of the upper die 20. Said fill-in member 19 is secured to one end of a spring 29, the other end of which is secured to the top plate 17. By this means the fill-in member 19 is normally held in the described position and supports the flap, until the upper die is depressed.

25, 25, indicate two side strips which are secured to the side walls 16, and serve as guides for the shoe-supporting slide shown in Fig. 4. This shoe-supporting slide comprises two plates, 26 and 27, spaced from each other and secured in fixed relation with arms 28, said plates being each provided with a step to receive a laterally sliding member 30, which co-operates in adjusting the mechanism to support a right or left shoe respectively in position to be operated upon, as below described.

An element 31 consisting of an L-shaped strip of metal, is secured at its shorter leg 32 to the sliding member 30, in such position that parts of said leg extend over plates 26 and 27. The leg 32 and sliding member 30 are slotted longitudinally, through which composite slot 33 extends the upper end of a guiding pin 34, the lower end of which is secured to a lever 35 and transmits the movement of said lever 35 to the member 30 and the L-shaped element 31 for the above-mentioned adjusting movement, the swinging movement of the lever 35 being translated into lateral sliding movement of the member 30 and element 31. The lever 35 is pivoted at 37 and manually operated by means of handle 39 on its forward end. The guiding pin 34 is provided with nut 36 on its upper end, to hold the L-shaped element 31 in its upright position.

The upright leg 38 of element 31 carries at its upper end a spring member 40, shown in detail view in Fig. 6. This member 40 is secured at its base to upright leg 38, and its arms 41 resiliently hold the front part of the last of a shoe to be operated upon, whereby the shoe stands upright. If desired to operate upon a shoe not having a last therein, the front part of the shoe itself may be supported by said spring arms 41.

At its lower end the shoe is supported by a cylindrical segment 42. Said segment is secured to and supported by one leg of a bent metal strip 43, the second leg 45 of strip 43 being held in upright position by screws 46, which screws extend thru slot 47 in the lower part of upright leg 38 of element 31, therefore by loosening the screws 46 and moving strip 43 up or down, the position of the shoe can be adjusted vertically and said screws thereafter tightened.

A scaled plate 48 (see Figs. 2 and 5) is mounted on top of the housing, the inner end of said plate extending to one edge of the lower die 18. On top of the scaled plate 48 and indicator 51 slides backwardly and forwardly, which can be adjusted with relation to the scaled plate and fixed in position by means of a knurled set screw 52. The numerals on the scale, indicated at 53, can be seen through a hole 54 of indicator 51.

50 is a guiding member fixed to the top plate 17 near the other cutting edge of the lower die, and co-operates with the inner end of scale plate 48 to bring the leather strip into laterally correct position.

In Figs. 11, 12 and 13 are shown the means for removing the scrap or trim. A pipe 80, the outlet of which is located near the location at which the trim, designated 81, remains on the surface of the lower die after the trimming operation has been completed, is connected to a valve 82 located on top of the top plate 17 of the housing. The valve 82 is opened and closed by means of a lever 83, and when opened permits a stream of compressed air to pass thru pipe 80, the air being conducted to the valve thru a pipe 84 (shown broken away at its outer end), from a compressor or any suitable source, not shown.

The lever 83 operates to open and close the valve by means of a pin 85 on its rear end. The forward end of the lever carries an extension 86, pivotally connected to the lever 83 by a pin in such manner that it may move downwardly relative to the lever, but not upwardly. A spring 87 secured to the lever 83 bears with its forward end against the under side of the extension 86, holding the extension normally in horizontal position. A stop 88 prevents the lever 83 from coming to a lower point than shown in Fig. 11, and a spring 90 pulls said lever downward until it normally rests on said stop 88.

This embodiment of the invention constitutes a unitary mechanism, which may be inserted in and actuated by any suitable press or other means, and removed therefrom when desired.

55 The operation of this embodiment of my invention is as follows: At the beginning of the operation, a skilled operator places in the machine a last bearing the upper, sole, and heel of one specimen of the particular type, style, and size of shoe (or, if desired, such a shoe without a last therein), a series of which is to be worked upon, the sole being split in the usual manner and the heel being affixed in its final correct position. To position the shoe, he draws the shoe-supporting slide outwardly by means of the handle 39, and while the shoe-supporting slide is thus extended places the shoe in an upright position, with the heel portion of the upper resting in the cylindrical segment 42, the affixed heel itself toward the housing, and the forward or upper part of the last (or of the shoe) being placed between the two arms 41 of spring member 40. Depending on the size of the shoe, the cylindrical segment 42 is adjusted vertically by loosening the screws 46 in slot 47, raising or

lowering the member 43, and tightening the screws at the desired position to bring the flap into the correct position for cutting. Prior to putting the shoe in the device, he marks with his finger nail or otherwise, on the right-hand edge of the flap, the exact location of the inner end of the extension of the heel, and when the supporting slide is pushed inwardly and the flap lies on top of the lower die 18 and the fill-in member 19, the finger-nail mark must lie exactly adjacent the pointed tip of the indicator 51, such indicator having been previously set to such one of the numerals designated 53 as corresponds with the length of the particular heel for which the flap is to be cut. To set the indicator 51, the knurled screw 52 is loosened, and again tightened after the indicator has been brought into position where the tip 55 points to the desired number of the scale.

Depending upon whether a right or a left shoe is to be worked upon, the L-shaped element 31, and with it the shoe, must be brought to the right or left side a certain predetermined distance, because the position of the center of the heel on a lady's shoe is spaced from the center line of the outsole. The transverse movement from right to left is derived from the swinging movement of the manually shifted handle 39, the lever 35, and the guiding pin 34, co-operating with the slot 33. The two plates 26 and 27 act as guides for the sliding member 30, to permit only straight transverse motion of the latter.

The adjustments being correctly made, the shoe-supporting slide is pushed rearwardly until the finger-nail mark on the flap (which flap then lies on top of the lower die 18 and the member 19) reaches the pointed tip of the indicator 51. This position is shown in Fig. 4. The flap is thus positioned correctly, and the press is then operated, the plunger of which depresses the laterally extending plate 23 and forces the upper die member 20 into shearing engagement with the lower die member 18 and thus cuts the desired shape of flap in exactly the desired and predetermined location, the fill-in member 19 being pushed downward to permit the shearing engagement of the dies.

On its upward movement, the plunger of the press releases its pressure on extending plate 23, the springs 22 push the plate 23 and with it the upper die member 20 into their original position, and the spring 29 restores the member 19 to its original position, wherein its upper surface is flush with the upper surface of the lower die.

The upward movement of the extending plate 23 moves the lever 83 of the valve 82 of the pneumatic blower (said blower not being shown), thus permitting compressed air to pass the valve 82 and thru the pipe 80, and blow away the trim remaining from the cutting operation. As soon as the plate 23 reaches its original position, however, the lever 83 is released therefrom and closes the valve 82, thus shutting off the air. On its downward movement, the extending plate 23 is enabled to pass the lever 83 by the downward pivotal movement of the extension 86.

The adjustments having been once correctly made, the operation may be repeated on successive shoes by an unskilled person, who can also, by merely swinging the handle, adjust the machine from right to left or vice versa. When a different size or shape of shoe is to be worked upon, new adjustments are made by the skilled operator, and if the flap is to be cut for a different type or height of heel, different dies are inserted.

In Figs. 7 to 10, a shoe supporting slide is shown which is modified in certain respects. The two arms of the slide (shown partly broken away) are spaced at the forward end, i. e., toward the right in Figs. 7 and 8, by a spacer 60, and at an intermediate point by a spacer 61. The transverse movement is performed by means of a sliding member 62 which slides on a rod 63, the ends of which are secured to the sliding arms. The lower leg 65 of an approximately L-shaped element 64 is slanted slightly upward toward the front, and is bifurcated at its inner or rear end, the arms 66 and 67 of which bifurcation are secured to the under side of the sliding member 62. A lever 68 is pivoted centrally on the under side of spacer 60; the outer end of said lever is provided with a handle for manual swinging operation, and the inner end is rounded substantially as shown and extends between and is embraced by the two arms 66 and 67, thereby translating the swinging movement of the lever 68 into a straight transverse movement of the sliding member 62 and the L-shaped element 64.

The upwardly extending leg 69 carries on its upper end a resilient holder 72, which can be formed of a strip of sheet metal, the forward end of said holder 72 being secured to the upper leg 69 and its rearward end being open, thus expanding in width when a shoe is placed therein. The form of this holder 72 is illustrated in Fig. 9, seen in the direction of the arrow 9 in Fig. 7, the position of the shoe when inserted therein being shown in part in Fig. 7.

At the lower end of the leg 69 of this L-shaped element 64, a screw 73 is provided, which supports the wire 74. This wire 74 forms an approximate U-shape, open toward the rear and its forward end being upwardly bent and wound around the screw 73 for attachment. The lower end of the shoe is supported by a cylindrical segment 76, analogous to segment 42 of Fig. 4, but provided with legs 77 having holes therethru closely fitting the wire 74, whereby the segment 76 slides on the two arms 75 of the wire 74.

The parts of this embodiment other than the shoe-supporting slide, are the same as or similar to those in the embodiment first described, and the operation of the modified embodiment will therefore be clear from the drawings and from what has been already said, without further description.

The operation of the present invention comprises the steps of first attaching the heel of the shoe in its final fixed position, then forming the flap to cover the breast of said heel, and thereafter securing said flap in place. In practice, the heels of a number of shoes would first be attached, the flaps then formed to correspond, and said flaps then secured in place. The method may be carried out by means of the machine as above described in connection with the operation herein set forth, or by any other suitable means or mechanism, or manually. The said method and its advantages will be clear from what has already been said as to the means of carrying the same out by the use of the machine herein described and shown, and it will also be obvious that the same may be carried out by other means or manually, while employing the above-named steps. By the use of my invention, a large number of heels may be affixed in final fixed position, and the flaps cut of predetermined uniform shape and correct location on the shoe, by the use of dies, a pattern, or otherwise, and then secured to the breast of the heel.

The advantages of the invention will be understood from what has been above said.

I do not limit myself to the particular details of construction and operation, which have been described in this specification or shown in the accompanying drawings, as it is obvious that the same may be modified in various ways, within the scope of the claims hereof, without departing from the spirit and scope of the invention.

Having thus described my invention, I claim:

1. A machine for forming heel flaps for shoes, comprising means for supporting a shoe having a heel attached in final position thereon, means for forming a flap of the sole of said shoe to conform to the breast of said attached heel, and means for moving and holding said shoe laterally relative to the central line of said flap-forming means, in each direction, to permit accurate operation upon a right or a left shoe.

2. A machine of the character described, comprising a housing, means for supporting in an approximately vertical position a shoe having its heel attached in final position thereon, means operative to form a flap conforming to the breast of said heel from a portion of the sole of said shoe, and means for adjusting the position of said shoe relative to said flap-forming means, said supporting and adjusting means comprising a shoe-supporting slide, guiding means for said slide, a laterally sliding member mounted in said slide, a shoe-supporting element carried by said sliding member, comprising a vertical portion, a cylindrical segment slidably adjustable with relation to said vertical portion for receiving the heel portion of said shoe, and a member secured to the upper part of said vertical portion and comprising resilient arms for positioning the upper portion of said shoe.

3. The construction defined in claim 2, together with a lever for moving said sliding member and its supported elements transversely relatively to the body of said shoe-supporting slide.

4. The construction defined in claim 2, together with adjustable indicating means for exactly indicating the correct position of said shoe for said forming operation.

5. The construction defined in claim 2, together with means for removing the trim remaining after said forming operation.

6. A machine for forming heel flaps for shoes, comprising means for supporting a shoe having a heel attached in final position thereon, means for forming a flap of the sole of said shoe to conform to the breast of said attached heel, and means for removing the trim remaining after said forming operation; said trim removing means comprising a source of compressed air, a valve for controlling the flow of said air, an outlet for said air adjacent the location of said trim, and a lever operated by said forming means for momentarily opening said valve upon the completion of the forming operation, said lever being operated in one direction by said forming means and being provided with a yielding extension at its outer end whereby said forming means may pass in the other direction without operating said lever.

7. A machine of the character described, comprising a housing, means for supporting a shoe having its heel attached in final position thereon,

means operative to form a flap conforming to the breast of said heel from a portion of the sole of said shoe, and means for adjusting the position of said shoe relative to said flap-forming means, 5 said supporting and adjusting means comprising a sliding member, guiding means for said sliding member, a laterally movable member carried by said sliding member, and shoe-supporting means carried by said laterally movable member, comprising a vertical member, a member slidably adjustable with relation to said vertical member for supporting the heel portion of said shoe, and a member secured to the upper portion of said vertical member and comprising arms 10 for positioning the upper portion of said shoe.

8. A machine of the character described, comprising a housing, means for supporting and positioning a shoe having a heel attached in final position thereon, and means operatively supported in said housing for forming a heel-breast flap conforming to the breast of said attached heel from a portion of the sole of said shoe, said supporting and positioning means comprising a carriage movably mounted for carrying said shoe 20 to and away from the flap-forming position relative to said flap-forming means, a shoe-support carried by and laterally movable with relation to said carriage, and means for moving and holding said shoe-support laterally in each direction from 25 the central line of said flap-forming means to permit accurate operation upon a right or a corresponding left shoe.

9. A machine for forming heel flaps for shoes, comprising a housing, means for supporting a 35 shoe having a heel attached in final position thereon, and a die operatively supported in said housing for forming a flap of the sole of said shoe to conform to the breast of said attached heel, said supporting means comprising a carriage 40 movably mounted for carrying said shoe to and away from the flap-forming position relative to said die.

10. A machine for forming heel flaps for shoes, comprising a housing, means for supporting a 45 shoe having a heel attached in final position thereon, and an upper and a lower die operatively supported in said housing for forming a flap of the sole of said shoe to conform to the breast of said attached heel, said supporting 50 means comprising a carriage movably mounted for carrying said shoe to and away from the flap-forming position relative to said dies.

11. A machine for forming heel flaps for shoes, comprising a housing, means for supporting a 55 shoe having a heel attached in final position thereon, and cutting means operatively supported in said housing for forming a flap of the sole of said shoe to conform to the breast of said attached heel by operation in a direction 60 substantially at right angles to the surface of the flap, said supporting means comprising a carriage movably mounted for carrying said shoe to and away from the flap-forming position relative to said cutting means.

12. The construction defined in claim 11, together with an adjustable finger for indicating the correct extent of movement of said carriage relative to said forming means to bring a shoe of a specific group to correct flap-forming position.

LOUIS SABO.
